(57) **CLAIM**

The ornamental design for a scoop head, as shown and described.

DESCRIPTION

FIG. 1 is an isometric view of the scoop head of the present invention;

FIG. 2 is a front elevational view of the scoop head of FIG. 1;

FIG. 3 is a rear elevational view of the scoop head of FIG. 1;

FIG. 4 is a left side elevational view of the scoop head of FIG. 1;

FIG. 5 is a right side elevational view of the scoop head of FIG. 1;

FIG. 6 is a top view of the scoop head of FIG. 1; and,

FIG. 7 is a bottom view of the scoop head of FIG. 1. The broken lines showing the handle illustrates the environment of the claimed design and forms no part thereof.

1 Claim, 4 Drawing Sheets
